(57) **CLAIM**

The ornamental design for a three-section storage shed, as shown and described.

DESCRIPTION

FIG. 1 is a front perspective view of a three-section storage shed embodying the principles of our new design;

FIG. 2 is a rear perspective view of the three-section storage shed;

FIG. 3 is a top view of the three-section storage shed;

FIG. 4 is a front view of the three-section storage shed;

FIG. 5 is a side view of the three-section storage shed as seen from the right hand side thereof;

FIG. 6 is a side view of the three-section storage shed as seen from the left hand side thereof;

FIG. 7 is a rear view of the three-section storage shed; and,

FIG. 8 is a bottom view of the three-section storage shed. The broken lines showing the bottom are for illustrative purposes only, and form no part of the claimed design.
